SHOE HEEL

Herbert August Strupp, Evansville, Ind.

Application June 28, 1944, Serial No. 542,479

5 Claims. (Cl. 36—35)

This invention relates to shoe heels, and more particularly to a shoe heel not operating as a shock-absorber but so constructed as to induce a normal exercising of the foot in walking or standing to promote the spread of synovial fluid, thus preventing set and allowing favorable action in cases of arthritis, ankylosis and other ailments.

The invention consists in the novel construction, arrangements and combinations hereinafter more particularly described and claimed.

One sheet of drawing accompanies this specification as part thereof, in which like reference characters indicate like parts throughout.

Figure 1 is a perspective view of the improved heel;

Figure 2 is a transverse cross-section taken on line 2—2 of Figure 1; and

Figure 3 is a medial vertical longitudinal cross-section taken on line 3—3 of Figure 1.

As herein illustrated, the heel is shown as a unitary device preferably constructed of rubber, which permits portions to be hardened by suitable treatment to a relatively noncompressible condition, while other portions are cured to a relatively compressible state. Obviously, the heel can be constructed of different materials if desired and the compressible and noncompressible portions associated by adhesives or in any other known manner.

However constructed, the heel embodies a medial longitudinal extending rib of relatively noncompressible material extending from front to rear of the heel associated with relatively soft and compressible portions on each side of said rib and also extending the full length of the heel from front to rear, thus providing a noncompressible pivot line centrally of the heel, permitting the heel of the user to rock transversely resiliently and thus exercises the ankle joint and promotes the spread and flow of the synovial fluid.

In the drawing, the heel in general is indicated at 1 and is shown formed with an upper layer 2 of relatively hard and noncompressible rubber, which layer is increased in thickness toward the longitudinal center of the heel until at a medial line of the heel this hardened portion extends the full depth of the heel, forming a central rib 3 extending the full length of the heel from front to rear. Preferably, and as herein illustrated, this thickening of the hardened portion of the heel is gradual and on an arcuate line, so that the side portions 5 of relatively soft and compressible rubber are of progressively increasing thickness from points adjacent the central hard rib to points adjacent the side of the heel, whereby the resiliency of the side portions 5 is increased toward the sides of the heel. Obviously, this line of demarcation between the hard central portion of the heel and the soft side portion of the heel

may be a straight line or any configuration desired, and the upper layer 2 may be omitted and the side portions extend to the top of the heel at the sides.

With a heel constructed as thus described, it will be apparent that the heel of the foot is permitted a resilient rolling movement to either side of the medial hard rib 3, both in walking and in standing, thus inducing a natural exercising of the ankle joint with the beneficial results indicated.

Having thus described my invention, I claim:

1. A shoe heel having a medial longitudinal rib extending the full length and depth of the heel of a relatively noncompressible material and side portions extending from said rib to the sides of the heel and extending longitudinally the full length of the heel, said side portions of a relatively compressible material to permit a resilient 5 rocking of the heel on said medial rib.
2. A shoe heel having a medial longitudinal rib extending the full length and depth of the heel of a relatively noncompressible rubber and side portions extending from said rib to the sides of the heel formed integrally with said rib but of relatively compressible rubber.
3. A shoe heel comprising an upper layer co-extensive with the heel, having a planar upper face for attachment to a shoe and its lower face 15 formed with a medial longitudinally extending rib, said upper layer and rib formed of relatively noncompressible material with side portions permanently associated with said layer and the opposite sides of said rib, said side layers formed 20 of relatively compressible material.
4. A rubber shoe heel having a top layer co-extensive with the heel and a medial longitudinally extending portion hardened to a substantially noncompressible condition and the longitudinally extending side portions cured to a relatively compressible condition, the medial longitudinal hardened part and said side parts having their outer faces in the bottom face and said parts separated by arcuate zones of demarcation 25 whereby said heel is given a substantially rigid central line of support extending from front to rear and relatively compressible side support increasing in compressibility from said central line outwardly to each side of the heel.
5. A shoe heel comprising a medial noncompressible portion extending from front to rear and the full depth of the heel, the sides of said portion inclined from the top of the heel inwardly toward the bottom face of said portion, with relatively compressible side portions extending from front to rear the full length of the heel, said side portions permanently attached to said inclined sides of said medial portion.

HERBERT AUGUST STRUPP.
